UNITED STATES PATENT OFFICE

128,540

DESIGN FOR A COMBINED COVER AND CAP FOR VAPORIZERS

Herbert L. Bennett, Pittsfield, Mass., assignor to
General Electric Company, a corporation of
New York

Application March 1, 1941, Serial No. 99,276

Term of patent 14 years

To all whom it may concern:

Be it known that I, Herbert L. Bennett, a citizen of the United States, residing at Pittsfield, in the county of Berkshire, State of Massachusetts, have invented a new, original, and ornamental Design for a Combined Cover and Cap for Vaporizers, of which the following is a specification, reference being had to the accompanying drawing, forming a part thereof.

Fig. 1 of the accompanying drawing is a top plan view of a combined cover and cap for vaporizers embodying my new design;

Fig. 2 is a front elevational view thereof; and
Fig. 3 is a side elevational view thereof.

The dominant features of the design reside in the portions shown in full lines.

I claim:

The ornamental design for a combined cover and cap for vaporizers, substantially as shown and described.

HERBERT L. BENNETT.
